Primary Examiner — Michael C Stout*Assistant Examiner* — Tia Ruth-Renee Polidori(74) *Attorney, Agent, or Firm* — Womble Bond Dickinson (US) LLP(57) **CLAIM**

The ornamental design for a beverage container, as shown and described.

DESCRIPTION

FIG. 1 is a top perspective view of my new design for a beverage container;

FIG. 2 is a bottom perspective view thereof;

FIG. 3 is a front elevation view thereof;

FIG. 4 is a rear elevation view thereof;

FIG. 5 is a right-side elevation view thereof;

FIG. 6 is a left-side elevation view thereof;

FIG. 7 is a top plan view thereof;

FIG. 8 is a bottom plan view thereof; and,

FIG. 9 is a cross-sectional view thereof taken along line 9-9 in FIG. 7.

The portions of the beverage container shown in evenly spaced broken line form no part of the claimed design. The dot-dash broken lines depict the bounds of the claimed design and form no part thereof.

1 Claim, 5 Drawing Sheets(56)
